J. P. WEIS,
OVERSTITCH MECHANISM.
APPLICATION FILED JAN. 2, 1919.

1,419,088.

Patented June 6, 1922.

Inventor

John P. Weis
By his Attorney
Edmund J. Beach

UNITED STATES PATENT OFFICE.

JOHN PETER WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

OVERSTITCH MECHANISM.

1,419,088.

Specification of Letters Patent. Patented June 6, 1922.

Original application filed October 16, 1914, Serial No. 867,005. Patent No. 1,348,526, dated August 3, 1920. Divided and this application filed January 2, 1919. Serial No. 269,279.

To all whom it may concern:

Be it known that I, JOHN PETER WEIS, a citizen of the United States, residing at Nyack, in the county of Rockland and State of New York, have invented certain new and useful Improvements in Overstitch Mechanism, of which the following is a specification.

This invention relates to over-stitch mechanism and this application is a division of my application Serial No. 867,005, filed October 16, 1914, patented August 3, 1920, Patent No. 1,348,526. The object of the invention is to separate the cut edges of goods and simultaneously to over-stitch one of such cut edges.

In the accompanying drawings forming a part hereof,

Fig. 1 is a detail elevation of a two-thread over-stitch mechanism looking in the direction of the arrow shown in Fig. 2. The view is partially in section through the throat plate and through cut goods the cut edges of which are separated.

Fig. 2 is a top plan view of what is shown in Fig. 1 and illustrates the making of the over-stitch on the goods.

Fig. 3 is a front end elevation of a sewing-machine head equipped with the present over-stitch mechanism and its actuating means.

Fig. 4 is a side elevation of what is shown in Fig. 3, the head being sectioned at line 4-4 of Fig. 3.

Figs. 5, 6, 7 and 8 are diagrammatic views showing different steps in the formation of the over-stitching.

That form of the invention shown in the drawings is particularly useful in automatic cutting-and-sewing machines of the type described in my Letters Patent No. 1,114,082 of October 20, 1914, and in my said pending application. It is not limited to such machines.

In the drawings, I show side-weighted or counter-balanced crank-and-pitman needle-actuating means such as shown in my aforesaid pending application and also in my application Serial No. 269,273 filed January 2, 1919, the latter being a division of my said pending application Serial No. 867,005, filed October 16, 1914. In the embodiment of the invention shown, the over-stitch mechanism is actuated from said side-weighted-pitman

needle-drive mechanism, and is particularly suited for high-speed production. The side-weighted crank 1, pitman 2, needle-holder 3 and needle 4 need not be particularly described.

The over-stitch mechanism comprises a link 5 pivotally connected to the crank pin of the crank at one end, and at its other end pivoted at 6 with one arm of a bell crank lever 7, the other arm of which is pivoted at 8 to a bracket 9 on the sewing-machine head. Between its ends the bell crank 8 is pivotally connected at 10 to a downwardly-extending link 11, the lower end of which is pivoted on stud 12 to the lower end of a lateral link 13 the upper end of which is pivoted at 14 to a bracket 15 which is a lower and divergently-extending portion of the bracket 9. The upper end 16 of the looper arm 17 is journaled on the pivot stud 12, being interposed between the lower end of the link 11 and the lower end of the link 13. This looper arm is pivoted at 18 between its ends to a link 19 which is pivoted at 20 to the bracket 15, but at a point below and nearer the needle than the pivot 14. The looper stem or portion below the pivot 18 is indicated by 21 and its lower end 22 is formed as a finger the purpose of which is to project into a space as α formed by cutting goods, and to remain between the walls of such cut to keep the cut edge being stitched from getting into the path of the laterally-projecting looper jaws 23 and 24 which are rigid lateral projections of the looper stem projecting therefrom into the path of the needle. This is illustrated in Fig. 2 where the slit α in the goods is formed by some goods cutter, not illustrated and not necessary to show. The bracket 9 carries a needle holder guide 25 whereby, as described in my said other applications, the needle is reciprocated in a vertical path through the throat plate P. The jawed looper device of the present over-stitch mechanism is mounted and operated at an angle to the feed of the material 26, the unstitched wall or edge of which is indicated by 27, and a portion of the cutter, although the cutting mechanism is not shown, is indicated by C because it operates sufficiently in advance of the needle to permit the looper jaws 23 and 24 to operate between the rear edge of the cutter and the needle in order to seize the loops of needle thread 28 under-

angle to the feed of the material 26, the unstitched wall or edge of which is indicated by 27, and a portion of the cutter, although the cutting mechanism is not shown, is indicated by C because it operates sufficiently in advance of the needle to permit the looper jaws 23 and 24 to operate between the rear edge of the cutter and the needle in order to seize the loops of needle thread 28 under-

neath the throat-plate tongue 29 drawing said loop out as shown in Fig. 6 so as to cast the same around the lower looper jaw 24 as shown in Fig. 7. The upper looper jaw 23 is a primary needle-loop receiving jaw and the under jaw 24 is the thread-carrying jaw, but in casting the loop on the lower jaw the thread comes from the upper jaw, all of which will be readily understood by those skilled in the art, as the arrangement of the looper jaws and the needle here shown are of themselves old and well known; but in the present case I have turned the old looper mechanism in question upside-down and reversed and relation of the jaws one to the other and provided the looper stem with a separator finger 22. However I am the first so far as I know to locate this old over-stitching mechanism above the throat plate and consequently above the work plate, and to provide means for working it from above the needle, but it is also to be said that in my present arrangement while the looper jaws reciprocate between a position above and a position below the throat plate, they also reciprocate through the slot or opening α formed in the goods by the cutter. In the present construction (Fig. 3) the looper stem is laterally off-set below its pivot 18 and a looper is mounted as already described, on the forwardly and outwardly projecting bracket 15. The result is that the looper jaws extend towards the needle diagonally to the line of cutting by the cutter C and to the line of stitching formed by the machine in which this looper mechanism is embodied. The diagonal relation is indicated in Fig. 2. The purpose of this arrangement is at all times to keep the looper as close to the edge of the slot in the goods that is being stitched as feasible; to cause the looper jaws to move into a position behind the needle when below the throat plate; to move into a position in front of the needle when above the throat plate properly to form the stitch; to secure a minimum projection of the looper jaws at one side of the path of the cutting run of the cutter C as is feasible in order that the opposite edges of the slot α may be separated a minimum distance. The V-shaped character of the cut shown in Fig. 2 is due in part to the springing apart of the cut edges as they are formed, and in part to the lateral vibration of the separator finger between their edges, the finger tending to push them slightly one way or the other, or by the independent action of the goods or of the separator finger according to the character of the goods acted upon. Tubular knit goods when slit after being distended on a spreader used in feeding the goods, spring apart at the cut edges to a considerable extent. Flat goods on the other hand would have the cut edges separated more particularly by the vibration of

the separator finger. The separator used in feeding knit goods is the device shown in my said prior patent and in my goods-spreader Patent No. 1,139,612 of May 18, 1915, and used in machines of the type of my Patent No. 1,114,082. As the looper rises, the needle thread loop slides back on the jaw 24 to the position shown in Fig. 7, at which time the looper thread 30 carried by the looper jaw 24 lies at an angle extending from the throat-plate tongue 29 to the front eye of the looper jaw 24 forming a triangle so that the point of the needle may enter between the looper jaw and the thread and draw the looper thread down on the upper surface of the work as indicated by 31 in Fig. 8. As the looper moves outward and downward the needle thread 32 drops from the end of the looper jaw 24 so as to form the stitches 33 (Fig. 2). 85

While the looper thread 30 forms the beaded edge 34 of the seam, the movements of the looper are such that the separator finger always remains within the slot α .

The looper mechanism is so timed in relation to the reciprocation of the needle that the looper is slightly slower in its movements than the needle is in its movements, and this difference in speed of timing permits the needle to deflect the needle thread 95 loop as shown in Fig. 5 for the entrance of the looper jaw 23 into the needle loop. Consequently the needle is rising ahead of the looper and starts to descend in time to enter the looper thread loop as the looper jaw 24 reaches the position shown in Fig. 7 the 100 needle enters the loop of looper thread to complete the formation of the stitch (Fig. 8). The throat plate 35 has a slotted needle-hole 36 and the work-holding foot 37 which is only partially shown herein is fully illustrated in my said application, Serial No. 269,273, filed January 2, 1919, and is provided with a projecting tongue 38 over which the stitches are formed, the slotted 110 needle-hole and work-foot tongue structure being known in over-stitch mechanism. 110

What I claim is,—

1. The combination, in a sewing machine, of a needle actuating mechanism operatively connected with a revolute shaft located above the throat plate; said shaft; and said throat plate provided with a hole for the needle and for a looper; a looper located above the throat plate; and a looper actuating mechanism located above the throat plate and operatively connected with said shaft for actuation of the needle actuating mechanism, whereby the shaft operates both the needle and the looper from above the throat 115 plate; the looper having near its lower end a pair of looper jaws and also having below the under jaw, at the free end of the looper, a dependent goods separating finger; and the looper actuating mechanism comprising 120

means to reciprocate it from above to below the goods and from below to above the goods and other means for vibrating the body of the looper above the throat plate from and 5 towards the needle path; a work holding foot having a projecting tongue over which the stitches are formed; and a goods cutting means operative adjacent the needle path.

2. The combination, in a sewing machine, 10 of a needle and needle actuating mechanism; a two-jawed looper and looper actuating mechanism and a goods cutter and mechanism for operating it adjacent the needle path for cutting the goods preparatory to the 15 stitching of a cut edge, the jawed looper being provided with a goods separator finger at its free end for entrance between the cut edges of the goods and separating the cut edges apart; and a work holding foot having 20 a projecting tongue over which the stitches are formed.

3. The combination, in a sewing machine, 25 of a needle; a needle reciprocating mechanism comprising a drive shaft; a two-jawed looper having a goods separator finger at its free end and mechanism for operatively con-

necting said looper with said drive shaft; a throat plate provided with a hole for the needle and for the jawed portion of the looper; a goods cutting mechanism operative 30 adjacent the path of the needle and of the jawed portion of the looper; and a work holding foot having a projecting tongue over which the stitches are formed.

4. The combination, in a sewing machine, 35 of a needle and needle actuating mechanism comprising a drive shaft; a two-jawed looper; a looper actuating mechanism operatively connected with the drive shaft; a goods cutter and cutter actuating mechanism for 40 operating the cutter to cut the goods preparatory to the stitching of a cut edge adjacent the paths of the needle and looper, the looper being provided at its free end with a goods separator finger entrant between the cut edges and operative to space 45 the cut edges apart; and a device cooperating with the two-jawed looper for formation of stitches.

In testimony whereof I have hereunto set 50 my hand this 27th day of December, 1918.

JOHN PETER WEIS.
